UNITED STATES PATENT OFFICE.

CHARLES W. BOUTILIER, OF BRITT, IOWA.

ROTARY ENGINE.

SPECIFICATION forming part of Letters Patent No. 613,223, dated October 25, 1898.

Application filed September 4, 1897. Serial No. 650,594. (No model.)

To all whom it may concern:

Be it known that I, CHARLES W. BOUTILIER, a citizen of the United States, residing at Britt, in the county of Hancock and State of Iowa, have invented a new and useful ⁵ Rotary Engine, of which the following is a specification.

My invention relates to rotary engines, and has for its object to provide a simple and efficient ¹⁰ construction and arrangement of parts adapted for adjustment with facility to reverse the direction of rotation, and to provide a rotary engine of the sliding cam-actuated abutment type wherein simple and efficient ¹⁵ means for packing and for concentrating the pressure of the motive agent upon the moving parts are employed.

Further objects and advantages of this invention will appear in the following description, and the novel features thereof will be particularly pointed out in the appended ²⁰ claims.

In the drawings, Figure 1 is a side view, partly in section, of a rotary engine constructed in accordance with my invention ²⁵ and showing in dotted lines the positions of the several ports and conductors. Fig. 2 is a sectional view taken parallel with and in the plane of the axis of the piston. Fig. 3 is a ³⁰ detail view in perspective of the piston. Fig. 4 is a similar view of one of the cylinder-heads to show the abutment-actuating cam carried thereby. Fig. 5 is a plan view, partly in section. Fig. 6 is a detail sectional view ³⁵ of one of the exhaust-controlling slides and contiguous parts on the line 6 6 of Fig. 1.

Similar numerals of reference indicate corresponding parts in all the figures of the drawings.

The casing 1 of the engine embodying my ⁴⁰ invention is mounted upon a suitable base 2 and is of sectional construction divided upon a mid-line, the members or sections being connected by suitable bolts engaging contacting flanges, and mounted in suitable bearings in the heads of the cylinder thus formed is the shaft 3 of the rotary piston 4. This piston is provided with a coaxial hub 5 and a concentric rim 6, which is equal in lateral ⁴⁵ projection to the hub from the plane of the web 7, which forms the body portion of the

piston. The peripheral rim and the hub preferably project equally upon opposite sides of the plane of the web to form opposite steam-chambers, in which operate the moving abutments or wings 8. These moving abutments are fitted terminally in alined grooves 9 and ⁵⁵ 10, formed, respectively, in the hub and rim of the piston, and operate in radial slots 11, registering with said grooves, whereby each ⁶⁰ abutment is adapted to occupy a position spanning either of the steam chambers or spaces, and hence to receive actuating-pressure upon either side of the plane of the web.

In order to secure the accurate rotary movement of the piston, I preferably provide it with a central peripheral rib 12, fitted in a cross-sectionally-coextensive groove in the inner surface of the casing or cylinder, and thereby interlocking the parts to prevent ⁶⁵ either endwise displacement or vibratory movement of the piston.

Arranged upon the opposite heads of the cylinder are segmental approximately semicircular enlargements 13, approximately ⁷⁰ equal in projection with the rim and hub of the piston beyond its intermediate web and of a radial width equal to the interval between the periphery of the hub and the inner surface of said rim. Each of these enlargements is terminally beveled to form cam-faces ⁷⁵ 14, which also perform the functions of fixed abutments, respectively, according to the direction of rotation of the piston, and hence according to the points at which the motive ⁸⁰ agent is admitted. The enlargements which terminally form the said fixed abutments are oppositely disposed upon the heads of the cylinder, and as each enlargement is approximately semicircular in length it will be seen ⁸⁵ that as the piston rotates each moving abutment or wing will be extended alternately beyond opposite sides of the web and piston, remaining in each position approximately throughout one-half of a revolution of the ⁹⁰ piston. Hence by placing feed-ports 15 in the enlargements, and preferably at the points of greatest projection of said cam-faces or fixed abutments from the heads, and arranging exhaust-ports 16 at intermediate points ⁹⁵ between the extremities of said enlargements I am enabled to apply motive agent to each ¹⁰⁰

piston wing or abutment throughout one-fourth of a revolution. Furthermore, by employing an uneven number of piston wings or abutments, preferably three, this relative dis-
5 position of feed and exhaust ports makes it impossible for the piston to stop at such a point that at least one of said wings shall not be wholly extended and hence wholly exposed to the pressure of motive agent admitted
10 through either of the feed-ports.

Any suitable arrangement of conductors for conveying motive agent to the several feed-ports and from the several exhaust-ports may be employed, provided the diametrically op-
15 posite feed-ports are connected to receive motive agent simultaneously, and in the con-
struction illustrated I employ feed-pipes 17 and 17^a for connecting the throttle-valve cas-
ing 18, with the upper feed-port in one head
20 and the lower feed-port in the other head, and employ feed-pipes 19 and 19^a for connecting the lower feed-port in the first-named head and the upper feed-port in the second-named head with said throttle-valve casing. The
25 feed-pipes 17 and 17^a communicate with a common feed-port in the throttle-valve cas-
ing, whereby steam or other motive agent is communicated simultaneously to the diamet-
rically opposite feed-ports of the cylinder, and
30 hence is applied in the same direction to the piston wings or abutments at opposite sides of the web of the piston.

Any suitable system of exhaust-valve mech-
anism may be employed, that which I have
35 illustrated consisting of segmental slides 20, seated in the inner surfaces of the cylinder-
heads and arranged terminally contiguous to the exhaust-ports, and I prefer to connect
said slides with the throttle-valve or revers-
ing-lever 21, by which the direction of applica-
40 tion of motive agent is controlled. In order to prevent back pressure of the motive
agent, I preferably arrange packing-strips 22
45 on the outer edges of the enlargements con-
tiguous to the beveled faces thereof, said
strips being spring-actuated to bear against
the inner surfaces of the projecting portions
of the piston-rim.

From the above description it will be seen
50 that each piston wing or moving abutment is devoid of springs or other actuating devices dependent upon tension, each being posi-
tively reversed in position by fixed cam-faces and each cam-face being radially equal in
55 length with the wings or abutments.

Packing devices have been shown at va-
rious points, as in the ordinary practice, to
prevent escape and loss of pressure; but it
is obvious that other equivalent means may
60 be substituted therefor and that various other
changes in the form, proportion, and the
minor details of construction may be resorted
to without departing from the spirit or sac-

rificing any of the advantages of this inven-
tion.

65

Having described my invention, what I
claim is—

1. A rotary engine having a casing com-
prising oppositely - positioned sections or
heads having inwardly-extending connected 70
flanges forming a cylindrical wall, a rotary
piston having a hub and a peripheral rim
connected by a web, from the plane of which
said hub and rim project in opposite direc-
tions, the rim being in contact with the inner 75
surface of the cylindrical wall of the casing,
the web being provided with a plurality of
radial slots, and the facing surfaces of the
hub and rim with guide-grooves registering
respectively with said slots at their opposite
80 ends, approximately semicircular enlarg-
ements projecting inwardly from the casing
sections or heads between the hub and flange
of the piston, and arranged alternately with
relation to the path of the piston, and wings
85 fitted to slide in said radial grooves of the
piston, with their outer and inner edges in
the grooves, respectively, of the rim and hub,
and hence in contact with the casing only
at their opposite side edges, substantially as 90
specified.

2. A rotary engine having a casing com-
prising oppositely - positioned sections or
heads provided with inwardly-extending con-
nected flanges having registering rabbets to 95
form an annular groove, a rotary piston hav-
ing a hub, a rim parallel with the hub having
contact with the inner surfaces of the flanges
of the casing-heads, an exterior rib 12 fitting
in said annular groove, a web 7 connecting 100
the hub and rim and arranged between the
side edges thereof, and in the plane of said
rib 12, the web being provided with a plural-
ity of radial slots, and the facing surfaces of
the hub and rim with grooves registering with 105
said slots respectively at the inner and outer
ends thereof, and wings fitted to slide later-
ally in said radial slots and arranged at their
outer and inner edges in the grooves, respec-
tively, of the rim and hub, approximately 110
semicircular, terminally cam-faced enlarg-
ements, projecting inwardly from the heads of
the casing between the facing surfaces of
said rim and hub of the piston, and arranged
alternately with relation to the path of the 115
piston-wings, and valve mechanism for con-
trolling the admission and exhaust of motive
agent, substantially as specified.

In testimony that I claim the foregoing as
my own I have hereto affixed my signature in 120
the presence of two witnesses.

CHARLES W. BOUTILIER.
